CLAIM

The ornamental design for a mobile broiler, as shown and described.

DESCRIPTION

FIG. 1 is a top view of a mobile broiler with the movable table unit in the extended position and embodying my new design;

FIG. 2 is a bottom view thereof;

FIG. 3 is a right side view thereof;

FIG. 4 is a left side view thereof;

FIG. 5 is a front view;

FIG. 6 is a rear view thereof; and

FIG. 7 is a top view of the mobile broiler but with the table unit in the retracted position.
